No. 734,481.

PATENTED JULY 21, 1903.

A. WENBERG.
TRACTION WHEEL.

APPLICATION FILED SEPT. 18, 1902.

NO MODEL.

UNITED STATES PATENT OFFICE.

ALFRED WENBERG, OF JOLIET, ILLINOIS.

TRACTION-WHEEL.

SPECIFICATION forming part of Letters Patent No. 734,481, dated July 21, 1903.

Application filed September 18, 1902. Serial No. 123,819. (No model.)

To all whom it may concern:

Be it known that I, ALFRED WENBERG, a citizen of the United States, residing at Joliet, in the county of Will and State of Illinois, 5 have invented certain new and useful Improvements in Traction-Wheels, of which the following is a specification.

My invention relates to improvements in traction-wheels adapted for use in connection 10 with and as the propelling means of motor-vehicles or sleighs; and the especial objects of my improvements are to provide a traction-wheel having gripping or frictional teeth adapted to contact with the earth or with 15 snow in a roadway, which teeth may be easily removed when worn out or broken and easily replaced by new teeth and which may be sharpened when they become dull from long or constant use.

20 A further object is to so mount or hang the wheel that it will adjust itself to uneven places in the road-bed, and thus remain in constant frictional engagement with the surface of the road and relieve the supporting- 25 frame of the jar or vibration which would result from a rigid mounting of the wheel.

A still further purpose of my invention is to construct a traction-tooth that will have a sharp edge and a broad base.

30 In carrying into effect the above-named objects and others of general utility and novelty I have designed the traction-wheel and mounting for same, shown in the accompanying drawings in preferred form by the following views.

35 Figure 1 is a side elevation of my improved traction-wheel mounted at the rear end of a frame. Fig. 2 is a transverse vertical section through my improved wheel on a scale 40 somewhat larger than Fig. 1. Figs. 3 and 4 are details of one of the traction-teeth.

45 Referring to the drawings in detail, A represents a pivoted extension of the frame of a vehicle of any desired form and means of connection and operation. The extension is bifurcated, as at a', to provide a way for the wheel C, which is mounted on an axle b', having bearings in vertically-slidable blocks b'. These blocks have grooves b³ formed in their

edges, which engage the tongues b⁴ on the 50 contiguous sides of the yokes b⁵, which are bolted to the rear ends of the extension A. The upper portion of the yokes are vertically bored to receive the rods b⁶, the lower ends of which bear against and are secured to the 55 upper portion of the blocks b². Mounted on the rods b⁶ between the blocks and the top of the yokes are springs b⁷, the tension of which is exerted against the blocks, but which yield when the wheel passes over ob- 60 structions in the roadway.

My improved wheel is formed with a U-shaped felly c', which is connected with the tubular hub c², preferably by wire spokes c³, in any well-known manner. The felly is 65 bored at points between the spokes to receive the shanks d' of the traction-teeth D, said shanks being threaded to receive the nuts d² on the under side of the felly. The base portion of the tooth embraced by the felly 70 conforms in shape to the contiguous sides of the felly and on the remaining sides curves outwardly, as shown, thus providing a wide base for the exposed or sharpened portion d³ of the teeth. The sides of the teeth which 75 extend across the felly are preferably formed concave, as at d⁴, thus retaining a sharp edge longer than if convex or merely straight. It will be noted that this construction gives the tooth a long bearing on the felly, thus holding it rigidly and preventing it from working loose. The extreme edge of the tooth is preferably slightly rounded, as shown.

Having thus described my invention, what I claim as new, and desire to obtain by Letters 85 Patent, is—

1. In a traction-wheel, a felly substantially U-shaped in cross-section, traction-teeth removably secured in said felly, said teeth having sides conforming to the shape of the felly, 90 and having sharp exposed edges.

2. In a traction-wheel, a tooth having a sharp outer edge, concave faces extending transversely of the tread of the wheel, and a broad base portion having its sides embraced 95 by and conforming to the wheel-felly, substantially as set forth.

3. In a traction-wheel, a concave felly hav-

ing outwardly-flaring sides and perforated at the bottom, traction-teeth having concave faces extending transversely of the felly, with a base the sides of which conform to the 5 shape of the felly, and with threaded extensions fitting the perforations of the felly, substantially as set forth.

In testimony whereof I affix my signature in presence of two witnesses.

ALFRED WENBERG.

Witnesses:

F. BENJAMIN,
JOHN HULSIZER.
